Specification of Letters Patent. Patented June 16, 1914.

Application filed December 18, 1911. Serial No. 686,585.

To all whom it may concern:

Be it known that I, ROBERT MIEHLE, citizen of the United States, residing at Chicago, in the county of Cook and State of Illinois, have invented a certain new and useful Improvement in Printing-Presses, of which the following is a full, clear, concise, and exact description, reference being had to the accompanying drawings, forming a part

10 of this specification.

My invention relates to printing presses and in its preferred embodiment it particularly relates to those printing presses employing reciprocating press beds and rack frames taking part in the reciprocation of the press beds and moving in the same directions with the press beds but at speeds which are reduced. I do not wish to be limited to this type of printing presses, however, in all 15 embodiments of the invention.

My invention has for its general object the provision of an improved construction whereby the weight upon the press bed is materially reduced and the size and weight 20 of the bed motion mechanism is materially lessened so as to minimize the momentum to be overcome when the press bed and bed motion parts are to be reversed and to arrange the bed motion mechanism in a compact 25 form so as to reduce the height and width of the press structure.

In accordance with my invention I detach the rack frame from the press bed and provide the rack frame with a slide or guide 30 way that is independent of the press bed and rollers upon which the press bed moves, motion being communicated to the press bed from the rack frame through a multiplying gear which causes the press bed to 35 travel in directions similar to the rack frame but at greater speeds. By this arrangement 40 the momentum to be overcome at reversals is greatly reduced.

It is another object of my invention to 45 provide improved speed retarding means and also the provision of means whereby the bed reciprocating mechanism may be thoroughly lubricated.

These features and other features of my 50 invention will be more fully set forth by a description of the preferred embodiment thereof shown by the accompanying drawings in which—

Figure 1 is a side view of a portion of a 55 printing press containing features of my in-

vention; Fig. 2 is an end elevation of a portion of the press; Fig. 3 is a side view, partly in section, showing other structural features of the press, the press bed being shown in its alternative extreme positions in 60 Figs. 1 and 3; Fig. 4 is a plan view showing features of bed reciprocating mechanism; and Fig. 5 is a view similar to Fig. 4 with the parts in different positions.

Like parts are indicated by similar characters of reference throughout the different figures.

The main driving shaft 1 has the main driving pinion 2 fixed thereupon, the shaft 1 also carrying a pinion 3 which is likewise 65 fixed thereupon, the pinion 3 serving to drive the cam shaft 4 through the intermediation of a spur gear 5 which is fixed upon the shaft 4. The cam shaft 4 makes one revolution to each complete reciprocation of 70 the press bed 6, and the impression cylinder 7 makes two revolutions to each complete reciprocation of the press bed. The impression cylinder is driven by the main shaft 1 through the intermediation of gears 2, 8 and 75 9. The gear 8 is fixed upon the shaft 10 which is journaled in the frame 11 in which the main shaft is also journaled. The gear 9 is co-axial with and is fixed with respect to the impression cylinder shaft 12 which 80 85 is journaled in the frame work 13.

An internal gear 14 is integrally formed with the gear 8 and is in mesh with the gear 15, this gear 15 being fixedly mounted on the outer end of the bed motion shaft 16 90 which is journaled in the bed motion frame 17. The bed motion frame is pivotally mounted on the frame 13 by means of a shaft 18. The bed motion frame is oscillated by mechanism that includes the arm 17¹ integral with the frame 17, the stud or cam roller 19 mounted upon the outer end of the arm 17¹ and a cam 20 fixed upon the cam shaft 4 and in engagement with the cam roller 19. The bed motion driving gear 21 100 is fixedly mounted on the inner end of the bed motion shaft 16, a face of the gear 21 carrying a crank pin upon which a crank roller 22 is disposed. The rack frame 23 carries racks 25 and 25¹ with which the 105 gear 21 is alternately engaged by the oscillation of the bed motion frame 17 whereby the rack frame receives its reciprocating movement longitudinally of the press bed. The travel of the rack frame is reversed by 110

the crank roller 22 which is brought into engagement with the rack frame owing to its confinement in the spaces 26, 26¹ which intervene between the shoes 27 (that are provided upon the ends of the rack frame) and, respectively, the shoes 27¹, 27² which are provided upon the free ends of the frames or gates 28, the shoes 27¹, 27² being arranged to swing in and out of the path of the crank roller 22. The gates 28 are pivotally mounted upon the rack frame. Rollers 29, 30, 31 and 32 are mounted at suitable places upon the gates 28, these rollers rolling upon the cams 29¹, 30¹, 31¹ and 32¹ respectively to swing the gates 28 in and out at the proper time as the rack frame is reciprocated. The cams 29¹ and 31¹ upon which the rollers 29 and 31 roll are short while the cams 30¹ and 32¹ upon which the rollers 30 and 32 roll are comparatively long. Set screws 33 and stops 33¹ hold the gates 28 while the short cams are inoperative.

Figs. 3 and 4 show the rack frame just at the point of reversal of the press bed at the end of the printing stroke. As the bed motion shaft 16 turns in the counter-clock-wise direction (as per Fig. 3) the crank roller 22, then within the space 26, starts the bed back on the non-printing stroke and gradually increases the speed of the rack frame until the crank roller 22 is at its lowest point, the speed of the rack frame equaling that of the periphery of the gear 21. During this time the cam 20 has lowered the gear 21 from a position central between the racks 25 and 25¹ to a position to engage the rack 25¹. When the crank roller reaches its lowest point and the gear 21 meshes with the rack 25¹, the cams 29¹ and 30¹ working in co-operation with the rollers 29, 30, respectively, swing the shoe 27¹ out of the path of the crank roller 22. The gear 21 then drives the rack frame and bed through the intermediation of the rack 25¹, until said gear has made one complete revolution, at which point the crank roller 22 is in position to enter the opposite space 26¹. The roller 22 is then confined in the space 26¹ by the shoe 27², actuated by the cams 31¹ and 32¹ which cause the shoe 27² to be positioned as illustrated in Fig. 5, whereby the rack frame and press bed are caused to slow down, are stopped, and are started in a reciprocal direction. During this time the cam 20 has raised the gear 21 into position to engage the rack 25. When the crank roller 22 has attained its highest point, the shoe 27² is swung out of the path of the crank roller 22 by the cams 31¹ and 32¹ working in co-operation with the rollers 31 and 32, respectively, as shown in Fig. 4 (the cams 31¹ and 32¹ have been omitted in Fig. 4 in order that the cams 29¹ and 30¹ may be seen more clearly). The gear 21 again drives the rack frame and press bed until said gear has again made a complete

revolution and the crank roller 22 is brought to its highest point in position to engage the space 26. At this point the shoe 27¹ has been swung into the path of the crank roller 22 whereby the rack frame and press bed are slowed down and are stopped at the end of the stroke with the crank roller 22 and the gear 21 in the positions shown in Figs. 3 and 4. The rack frame 23 is supported by and slides upon guide ways 34 located upon the sides of a lubricating oil receiving channel 34¹. The rack frame is provided with extensions 35 that support a shaft 36 upon which is fixed a multiplying gear 37, this gear being disposed between said extensions 35. The rolling gear 37 is in continuous engagement with the press bed rack 38 and the stationary rack 39, the rack 39 being fixed upon the bottom of the aforesaid stationary oil channel 34¹. As the rack frame 23 is reciprocated, the gear 37 is also bodily reciprocated and rolls upon the stationary rack 39 whereby the rack 38 and the press bed 6 to which the rack 38 is attached are caused to move at twice the speed and double the travel of the rack frame owing to the function of the multiplying gear 37. The air cushioning cylinders 40 and 40¹ are secured at the ends of the channel frame 34¹ while piston rods 43 carrying piston heads 44 are provided upon each end of the rack frame 23, said cylinders receiving the pistons at the ends of the rack frame strokes whereby the speed of the retarding piston is reduced as compared with the speed of the press bed 6 and whereby the same retarding device serves the purpose of checking the travel of the press bed and rack frame, so that the rack frame and press bed need not be individually supplied with speed retarding devices. By checking the travel of the press bed through the intermediation of a more slowly moving part traveling in the same direction with the press bed, such as the rack frame, larger speed retarding cylinders and pistons may be employed. The size of the retarding devices should be adapted to the loads they are to overcome. The limiting size of the retarding cylinders 40¹ is shown by the dotted circle 45 in Fig. 2. In some cases cylinders of this size will not be sufficiently effective where they are employed in connection with especially heavy presses, as perfecting presses and two-color presses on which two press beds are used in one machine, or lithographic presses where heavy stones are used on the press beds. I therefore, in such cases, supplement the retarding devices 40, 40¹ etc. that indirectly operate upon the press bed by retarding devices that are directly operated upon by the press bed, these supplemental speed retarding devices including pistons 41 carried upon the opposite portions of the press bed and working within stationary cylinders 41¹.

Many of the characteristics which I have described are, broadly speaking, well known to those skilled in the art and further description of the mechanism which is known to those skilled in the art will not be necessary. It will be recognized, however, that I have evolved many improvements over the prior art, in addition to the retarding mechanism above described and I will more specifically point out those improvements to which attention has not been particularly directed in the foregoing description.

As the invention is illustrated the rack frame has non-vertical movement, but I do not limit myself to this characteristic. This rack frame is provided with means, which have been set forth, for slidably supporting it independently of the press bed and the rollers that support the press bed whereby the construction and assembly of certain of the press parts are greatly simplified and made more compact, features of much importance in a printing press structure in which the press bed and rack frame move in similar directions at differential speeds.

By reference to Fig. 2 it will be seen that the rack frame 23 of my organization is disposed substantially between the planes of the press bed rack 38 and the stationary rack 39 whereby the height occupied by the press bed reciprocating mechanism is materially reduced as compared with the presses of the prior art. It will be seen that the rack frame is interposed between the press bed rack 38 and the stationary rack 39 whereby the width occupied by the press bed reciprocating mechanism is materially reduced as compared with the press bed mechanisms of this type in the prior art. By locating the speed increasing gearing 37 upon an end of the rack frame such gearing is caused to travel in the space in which the rack frame travels, whereby the width of the press bed reciprocating mechanism is reduced irrespective of the location of the rack frame between the racks 38 and 39. The press bed reciprocating mechanism, in being made more compact, not only reduces the space occupied by such mechanism with advantages that must be readily appreciated, but the press bed is caused to reciprocate in directions similar to the rack frame by power transmitted through shorter distances so that the operation is more positive and whereby the tendency to vibration is materially reduced. Moreover, the weight of the bed motion mechanism is materially lessened whereby the momentum which is to be overcome when the press bed is reversed is minimized. The portion of my improved printing press that includes the oil channel 34¹ is also of importance, since oil may be contained within this channel to a depth that will include the teeth of the stationary rack 39 to reduce wear upon these teeth and

the teeth of the multiplying gear 37 meshing therewith. The teeth of the gear 37 will transfer oil to the teeth of the traveling press bed rack 38 from which the oil will drop upon the rack frame 23, bed motion racks, bed motion gear, and the crank mechanism 22, the crank roller 22 also dipping into the oil when the crank roller reaches its lower position. In order to prevent the oil from dripping to the floor when the rack 38 is at the farther point at the end of the non-printing stroke, I employ an oil conveying shield or channel 42 which is made sufficiently long to catch the oil dripping from the rack 38 and which shield is employed as a duct or channel way to carry the oil received therein back to the main oil channel 34¹, the oil mainly finding its way back to this channel through the bearings of the multiplying gear 37 as illustrated most clearly in Figs. 1, 4 and 5. The channel way 42 is desirably bifurcated so as to afford two branches that straddle the multiplying gear 37, while the bearings for the multiplying gear are desirably provided with holes 46 through which the oil may readily find passage to the shaft 36. In this way all of the principal parts of the bed motion mechanism are automatically lubricated.

Features shown and not claimed herein are claimed in co-pending application Serial No. 625,050, filed May 4, 1911.

While I have herein shown and particularly described the preferred embodiment of my invention, I do not wish to be limited to the precise details of construction shown as changes may readily be made without departing from the spirit of the invention.

Having thus described my invention I claim as new and desire to secure by Letters Patent the following:

1. A printing press having a reciprocating press bed and including a reciprocated rack frame; gearing for effecting reciprocation of the rack frame; a rack carried by the press bed; an additional rack; and gearing operated by the rack frame and operating upon said racks whereby the press bed is reciprocated in directions similar to the reciprocations of the rack frame, the rack frame being disposed substantially between the planes of said racks.

2. A printing press having a reciprocating press bed and including a reciprocated rack frame; gearing for effecting reciprocation of the rack frame; a rack carried by the press bed; an additional rack; and gearing operated by the rack frame and operating upon said racks whereby the press bed is reciprocated in directions similar to the reciprocations of the rack frame, said frame being interposed between said racks.

3. A printing press having a reciprocating press bed and including a reciprocated

rack carried by the press bed; an additional rack; speed increasing gearing operated by the rack frame and operating upon said racks whereby the press bed is reciprocated in directions similar to the reciprocations of the rack frame and at increased speed with respect to the speed of travel of the rack frame, said frame being interposed between said racks; and means whereby the rack frame is supported in its movements independently of the means by which the press bed is carried upon the press bed support.

13. A printing press having a reciprocating press bed and including a reciprocated rack frame; gearing for effecting reciprocation of the rack frame; a rack carried by the press bed; an additional rack; and speed increasing gearing operated by the rack frame and operating upon said racks whereby the press bed is reciprocated at increased speed with respect to the speed of travel of the rack frame, said frame being interposed between said racks.

14. A printing press having a reciprocating press bed and including a reciprocated rack frame; gearing for effecting reciprocation of the rack frame; a rack carried by the press bed; an additional rack; and speed increasing gearing operated by the rack frame and operating upon said racks whereby the press bed is reciprocated at increased speed with respect to the speed of travel of the rack frame, the rack frame being disposed substantially between the planes of said racks.

15. A printing press having a reciprocating press bed and including a reciprocated rack frame; gearing for effecting reciprocation of the rack frame; a rack carried by the press bed; an additional rack; and speed increasing gearing carried upon an end of and operated by the rack frame and operating upon said racks whereby the press bed is reciprocated in directions similar to the reciprocations of the rack frame and at increased

speed with respect to the speed of travel of the rack frame.

16. A printing press having a reciprocating press bed and including a reciprocated rack frame; gearing for effecting reciprocation of the rack frame; a rack carried by the press bed; an additional rack; and speed increasing gearing carried upon an end of and operated by the rack frame and operating upon said racks whereby the press bed is reciprocated at increased speed with respect to the speed of travel of the rack frame.

17. A printing press having a reciprocating press bed and including a reciprocated rack frame; gearing for effecting reciprocation of the rack frame; a rack carried by the press bed; an additional rack; and speed increasing gearing carried upon an end of and operated by the rack frame and operating upon said racks whereby the press bed is reciprocated in directions similar to the reciprocations of the rack frame and at increased speed with respect to the speed of travel of the rack frame, said speed increasing gearing being located in the space in which the rack frame travels.

18. A printing press having a reciprocating press bed and including a reciprocated rack frame; gearing for effecting reciprocation of the rack frame; a rack carried by the press bed; an additional rack; and speed increasing gearing carried upon an end of and operated by the rack frame and operating upon said racks whereby the press bed is reciprocated at increased speed with respect to the speed of travel of the rack frame, said speed increasing gearing being located in the space in which the rack frame travels.

In witness whereof, I hereunto subscribe my name this 15th day of December A. D., 85
1911.

ROBERT MIEHLE.
